UNITED STATES PATENT OFFICE

HUGO MUTSCHLER, OF LINDELFINGEN, GERMANY, ASSIGNOR TO INTERNATIONAL TIME RECORDING COMPANY OF NEW YORK, OF ENDICOTT, NEW YORK, A CORPORATION OF NEW YORK

TIME RECORDER

Application filed June 13, 1928, Serial No. 285,004, and in Germany November 25, 1927.

- This invention relates to time recorders for printing a record of the elapsed time between successive registrations of an operator made at the beginning and end of a job, and more particularly to such recorders as in addition indicate the time at which the registrations are made.
- Known recorders of this type indicate the time at the beginning and end of a job by printing a reproduction of a clock dial with radial indicators to point to the time. The objection to these recorders is that the time can be arrived at only approximately because interpolation is required.
- 15 The object of this invention is the provision of means for overcoming the above objection by printing in numerals at the side of the elapsed time record, a record of the hour, minute, and fraction of a minute at which a registration is made.
- 20 The object is further to print the time at the beginning and the end of a job by means of a single printing mechanism.
- 25 The object is still further to print the date alongside the time indications by means of said printing mechanism.
- Another object is to provide a novel construction of the printing mechanisms for recording the elapsed time.
- 30 Still another object is to provide means for indicating the position of the record card with respect to the printing mechanisms.
- Various other objects and advantages of my invention will be obvious from the following particular description of one form of mechanism embodying the invention or from an inspection of the accompanying drawings: and the invention also constitutes certain new and novel features of construction and combination of parts hereinafter set forth and claimed.
- In the drawings:
- Fig. 1 is a skeleton plan view of the machine.
- 45 Fig. 2 is a skeleton sectional view of the machine and
- Fig. 3 is an example of a record made by the machine.
- 50 Referring to the drawings in detail, the printing mechanism for printing the time
- at the beginning and end of a job and the corresponding dates includes a type wheel 1 provided with numbers 0 to 23 for printing the hours, a type wheel 2 provided with type indicating the minutes and fractions thereof, 55 and type wheels 3 and 4 for printing the day and month respectively. These wheels are rotated at the various required rates in any convenient and well-known manner from a horizontal shaft 5 actuated by clock mechanism 6 (shown diagrammatically in Fig. 1). The date wheels may be manually set.
- The printing mechanism for printing the elapsed time is driven from shaft 5 through a clutch connection 7, releasable by manipulation of a member 8. The clutch serves to actuate a shaft 9 which through gearing 10 drives the various wheels of the elapsed time printing mechanism. This mechanism comprises an outer annular die 12 having type on 70 its upper face for printing hour circle 12a, the die being rotatably journaled on a vertical shaft 13 which rigidly carries an inner circular die 14, the upper face of which is on a level with the printing face of die 12 and is provided with a rib for printing arrow 14a. A second shaft 15 parallel to shaft 13 has rotatably journaled thereon an annular die 16 for printing arrow 16a and has rigidly fixed thereto an inner die 17 with printing face on 75 a level with the printing face of die 16 and adapted to print the inner circle 17a indicating tenths and twentieths of an hour.
- Gearing 10 is designed to rotate dies 12 and 16 at the same rate with the arrow on die 16 80 on a radius parallel to that bisecting the numeral 0 on die 12. Dies 14 and 17 are also rotated in synchronism with the arrow on die 14 pointing in the direction of a radial line drawn to numeral 0 on die 17.
- A member 18 is provided to abut the edge of the card and selectively position it over the dies for printing the elapsed time. A lever 20 is pivoted at one end to member 18 and at its other end to a slide 21 movable on base 22. 85 Slide 21 is formed with a pair of inclined oppositely facing cam edges 23 and 24 adapted to cooperate with the lower ends of shafts 13 and 15 to raise said shafts selectively. Thus when the registration is made at 100

the beginning of a job, member 18 is moved to its extreme left hand position and causes the cam edge 23 to raise shaft 13 to its uppermost position where the printing face of the dies thereon are on a level with the type in printing position on the wheels 1, 2, 3 and 4 for printing the time and date at the beginning and end of a job. The cam surface 24 at the same time will have permitted shaft 15 to drop to a lower position. Hence upon actuation 10 of the stamping block 25, the dies 12 and 14 will make an imprint on the record card of circles 12a and arrow 14a, respectively, and wheels 1, 2, 3 and 4 will print the time and date on a line 26 alongside circuit 12a. At 15 the end of a job, member 18 is shifted to the extreme right moving cam edges 23 and 24 to the left and causing shaft 13 to lower and shaft 15 to move upward to a level with printing wheels 1, 2, 3 and 4. Upon actuation of 20 stamp 25, the imprint will be made of circle 17a and indicator 16a together with the actual clock time 27 at the end of the job. In order to definitely determine the position of member 18 for printing at the beginning and end 25 of a job, an indicator 28 is provided in one side of said member which for the beginning registration will point to a suitable indication such as the word "beginning" and for the ending registration will point to an indication 30 such as the word "ending".

While I have shown and described and pointed out the fundamental novel features of the invention as applied to a single modification it will be understood that various omissions and substitutions and changes in the form and details of the device illustrated 35 and in its operation may be made by those skilled in the art without departing from the spirit of the invention. I intend to be limited therefore only as indicated by the scope of the following claims.

1. A device for recording elapsed time between successive registrations, comprising a 40 die for making an imprint upon the first registering operation, a die for making an imprint upon the second registering operation, record card positioning means and means controlled by the latter for selecting one of the dies for operation.

2. A device for recording elapsed time between successive registrations, comprising a 45 die for making an imprint upon the first registering operation, a die for making an imprint upon the second registering operation, card positioning means, and means actuated by the latter for selectively raising one of the dies into printing position.

3. A device for recording elapsed time between successive registrations, comprising a 50 die for making an imprint upon the first registration, a die for printing upon the second registration, shafts carrying said dies, card positioning means, and means operated 55 by the latter for selectively raising said

shafts to place said dies in printing position.

4. A device for recording elapsed time between successive registrations comprising a die for making an imprint upon the first registration, a second die for making an imprint upon the second registration, card positioning means, and means operated by the latter for automatically placing the first-named die in printing position upon the first registration and for automatically placing 70 the second die in printing position upon the second registration. 75

5. A device for recording elapsed time between successive registrations, comprising a die for printing upon the first registration, 80 a die for printing upon the second registration, a card positioning means and cam means operated by the latter for selectively locating said dies in printing position.

6. A device for recording elapsed time between successive registrations, comprising a die for printing upon the first registration, a die for printing upon the second registration, a card positioning means, and a slide actuated by the latter upon positioning a 85 card for selectively locating the dies in printing position.

7. A device for recording elapsed time between successive registrations, comprising a die for making an imprint upon the first 90 registering operation, a die for making an imprint upon the second registering operation, record card positioning means, means for selecting one of the dies for operation, and a connecting member between both of 95 said means to connect them for coordinated operation.

8. A device for recording on a card the elapsed time between successive registrations, comprising a die for recording upon 100 the first registration, a die for recording upon the second registration, and a single member operable to select either one of said dies for recording operation.

9. A device such as described in claim 8, 105 said member being differentially movable in accordance with which die is to be selected for printing operation.

10. A device such as described in claim 8, 110 said member simultaneously moving both said dies, one into printing position and the other out of printing position.

11. A device for recording on a card the elapsed time between successive registrations, comprising a pair of spaced shafts, a 115 set of inner and outer dies carried by each shaft and fixed against axial movement thereon, and commonly operated means for alternately axially moving said shafts to alternately position the complete set of dies 120 on each shaft for a single printing operation, both said sets of dies cooperating to record elapsed time.

12. A device for recording elapsed time 125 between successive registrations, comprising 130

a die for making an imprint upon the first registration, a die rotating in synchronism with the first-named die for making an imprint upon the second registration to indicate the elapsed time between registrations,
5 a pair of spaced shafts for carrying said dies, a member for selectively positioning a card into the same location relative to each shaft to receive an impression from the die carried by each shaft, and means for alternately actuating said dies to position them for printing on the card.
10

13. A recording device comprising a time-operated die for making an impression on a card upon one registering operation, a second time-operated die for making a correlated impression on the card upon a succeeding registering operation, and a member operable to selectively position a card into operative location with respect to either of said dies.
15

14. In a device for making an elapsed time record on a sheet by means of rotary time-controlled dies upon successive selective operation of the dies; means for making a record along parallel straight lines of the actual time at which each elapsed time operation occurs, said means comprising a rotary printing die with its axis disposed at right angles to the axes of the elapsed time dies, the effective printing surfaces of all of the dies being in the same plane, and a single member for effecting simultaneous printing operations by the actual time die
25 and one elapsed time die upon the first registration and by the actual time die and the other elapsed time die upon the second registration.
30

15. A device for recording elapsed time between successive registrations, comprising a die for making a record upon the first registration, a die for making a related record upon the second registration, means for selecting either one of said dies at a time and
40 a single operating device for causing operation of said means to select the dies one at a time.
45

In testimony whereof I hereto affix my signature.

50 HUGO MUTSCHLER.
